Fig. 1.

Fig. 2.

Fig. 3.

To all whom it may concern:

Be it known that I, Charles L. Cochran, a citizen of the United States, residing at Overland Park, in the county of Johnson and State of Kansas, have invented a new, original, and ornamental Design for an Airplane, of which the following is a specification, reference being given to the accompanying drawing, forming a part thereof.

Fig. 1 is a top plan view of an airplane, showing my new design.

Fig. 2 is a side elevational view thereof; and

Fig. 3 is a front elevational view of the airplane.

The bottom of the airplane is the same as the top except for the rudder vanes.

I claim:

The ornamental design for an airplane, as shown and described.
